UNITED STATES PATENT OFFICE.

GEORGE SUTHERLAND DODMAN, OF LIVERPOOL, ENGLAND.

AERIAL AND LIKE VESSEL.

1,144,177.

Specification of Letters Patent. Patented June 22, 1915.

Application filed July 17, 1914. Serial No. 851,549.

To all whom it may concern:

Be it known that I, GEORGE SUTHERLAND DODMAN, a subject of the King of England, residing at "Samara," Windsor Road, Tue Brook, Liverpool, in the county of Lancaster, England, have invented new and useful Improvements in or Connected with Aerial and Like Vessels, of which the following is a specification.

10 This invention has reference to air-ships and particularly to those which employ an engine or engines and propellers for propelling them, and receive their buoyancy wholly or partly from a gas lighter than air; and the object of the invention is generally to provide improvements in connection with this class of air-ship.

The invention, further, has reference to that special type of air-ship which is divided up into a plurality of sections, with chambers between them; and the whole is comprised within an outer frame, made up primarily of longitudinal, circumferential or transverse framework, with an outer 25 covering or skin. In cross section, the ship in general form is more or less of horse-shoe shape; and the space between the two corners which come at the lower parts or heels of the shoe shape—which of course is 30 closed—is concave, *i. e.*, curved upward, the lower corners being themselves round. The ship is without platforms, rooms or projections of an analogous kind below its body proper, and is constructed and adapted to 35 take to the water and float upon it, if and when desired. Each of the two corners in the section of the ship constitutes as it were, a keel fore and aft; and a water ballast tank or tanks may be disposed in them, so 40 as to give the vessel stability when supported either wholly or partially when lying on the water; and oil fuel store tanks may be placed above or alongside these water tanks, in the chambers between the sections. 45 The craft therefore, constitutes a hydro-aerial ship.

The air-ship is provided with a transverse longitudinal or fore and aft deck, say about the middle, and it will also have vertical divisions longitudinally, so that in the main section through the ship, there will be four gas envelops, one in each quarter. Between each section there is a chamber or space—relatively narrow—which serves as a 50 chamber for passengers, propelling engines of the ship, guns, provisions, and so forth;

and the said chamber beneath and above the deck are disposed so that one, say that in the lower half of the ship, as regards the transverse plane, will be at a point midway 60 between the transverse planes in which two of the sections of the chambers in the upper part of the ship lie.

In the same plane as the chambers between the sections, and respectively above 65 and below these chambers in the lower and upper half of the ship, there are ballonnets which are acted upon by the gas envelops, contained in the main buoyancy sections of the vessel; so that they serve to collapse, 70 and thus allow for the expansion of the gas in the gas bags by heat, as the temperature varies, and to compensate for the expansion and contraction of such gas as it becomes heated or cooled. And within the vertical 75 divisions, which may be frames spaced apart, there will be a passage formed above the horizontal—and preferably concave—deck, and also one in the lower portion of the lower division, directly above the lower 80 floor.

An air tube of substantial diameter extends fore and aft through the upper part of the ship, say directly above the passage on the deck, the purpose of which will be 85 hereafter explained.

The invention will be described with the aid of the accompanying drawings.

In the drawings, Figure 1 is a longitudinal outside elevation of the ship; and 90 Figs. 2, 3, and 4 are sections through it, taken at the line AA, BB and CC, respectively. Fig. 5 is a longitudinal section of a portion of the ship; Fig. 6 is a plan in section, showing means of operating and controlling the ventilators. Fig. 7 is a transverse view; and Fig. 8 a side view, showing the air shaft, passages, struts, and a portion of the ventilating system. Fig. 9 is a section illustrating in detail the system of 95 "frame bracing"; and Fig. 10 is a plan. Fig. 11 is a longitudinal section; and Fig. 12 a detail of same. Figs. 13 and 14 show in detail vertical struts extending through the ship between the sectional division chambers, and the passages, and upper ventilating means. Fig. 15 is a side elevation; and Fig. 16 a plan illustrating the air shaft entrance, and form of the bow of the ship. Fig. 17 is a view showing the longitudinal 100 and vertical air shafts; the front portion of which is a vertical view, and the rear nor-

tion a plan showing the bifurcated discharge conduits. Fig. 18 is a section through one of the frame members, showing the attachment of the outer water-proof skin or sheathing. Fig. 19 shows in plan a set of movable vertical wings disposed on the side of the ship.

Referring to the drawings, 1 represents generally the outer framing of the ship; and 10 2 is a deck extending through the ship at about the middle, it being slightly concave.

3 are the lower chambers existing between the different lower sections of the ship, beneath the deck 2; and 4 are similar chambers 15 provided between the upper sections of the ship, above the deck or bulkhead 2; the chambers 3 of the lower half of the ship, being disposed at points intermediate to those of the upper half of the ship.

20 As shown by the sections in Figs. 2, 3, and 4, the ship in general form and cross section is more or less of horse-shoe shape; and the part of the hull between the two lower corners 5 is convex, that is, curved upward, the lower corners 5 themselves being rounded, forming keels extending fore and aft of the ship; and as shown in Fig. 4 a water ballast tank 6 may be provided in each of them in the chambers 3, and also oil tanks 30 for storing oil for the propelling motors of the ship. These tanks will give the vessel stability when lying on the water.

The keel portions or corners 5 may be provided with a sheathing 8 as shown in Fig. 2, 35 for the purpose of preventing the ordinary textile or like water-proof sheathing, from being damaged when landing.

10 is an upper passage extending between the bow and the stern of the ship, directly 40 above and upon the horizontal deck 2; and 11 is a similar passage extending between the bow and stern, directly upon the bottom of the ship, and these passages are inclosed by a casing of light timber. These passages 45 have sliding doors 12 in them, on each side, for gaining access to the gas envelop chambers through which they pass; and they also have sliding doors 13 in their roofs for the purpose of ventilation. And the doors 13 50 will be disposed at suitable intervals, and all connected up with suitable cords or connections 14 which terminate in handles 15, in the chambers 3, 4, the cord passing round a pulley 16 at one end of each section of the ship. So by pulling in one or other cord or chain, the device can be opened more or less, or closed.

At the end of each section of the ship where a passage leads out of and into the 60 chambers 3 and 4, there will be provided a transverse sliding door 17 (see Figs. 2 and 4) so that these passages may be closed at both ends as and when desired. And at these parts also, there is provided a tunnel section 20 which normally lies in one of the

passages, and which may be moved longitudinally so as to form a continuous connection between the two sections of the adjacent 75 passages on each side of the chambers 3 and 4; and these tunnel portions 20 may have double sliding doors 21 in their sides, which will open into the chambers 3 and 4, so that access can be had to and fro, between the chambers and the passage, when the tunnels are moved into position. Thus by these 75 doors and passages, the various parts and chambers of the ship may be put in communication with one another, or cut off from same, whenever occasion for so doing may arise.

The air tube extending through the ship is designated 23; and it lies directly above the upper passage 10; and vertical branch tubes 24 extend through the chambers 4 from this passage to the top of the ship; and 80 at the upper ends, above the ship's surface, elevating fans 25 are provided at their entrance, adapted to be worked preferably by electric motors; and each branch conduit 24 has a throttle valve 26 in it, by which it 85 can be closed more or less, or opened. And the lower end of these branches, where they pass or merge into the main conduit 23, are bent in an "aft" direction.

Within the tube 23, electrically, or other 90 propelled fans (as indicated at 27, Figs. 5 and 17) are employed to assist the fans 25, and force air aft.

The forward end of the shaft 23 is provided with an expanded and downwardly 100 directed nose, 28 (see Figs. 15, 16 and 17); and it has in it a valve 29 by which it can be opened and closed as and when desired; and at the stern, the tube or shaft 23 is bifurcated into two conduits, which discharge more or less right and left; and at the point of bifurcation there is provided a valve 30, which may direct the air either to the one or other passage, or partly to the one, and partly to the other. By these 110 means, according to the position of the valve and the direction of discharge of air which leaves the ship, so will the ship be moved and steered horizontally.

As will be seen by Figs. 15 and 16, more 115 particularly, the nose or bow of the ship in plan is approximately parabolic; and vertically approximately hyperbolic; and the apex or actual stem, horizontally, is tilted upward as shown in Fig. 15, and stands 120 slightly above the central horizontal plane of the ship.

In the upper part of the ship, ventilating shafts 32 are provided in each section; and above them are ventilator cowls 33; and 125 these ventilating shafts 32 have in them apertures, governed by doors, which are operated in the same manner as the ventilator doors 13 of the passages 10 and 11, and operating in a similar manner, so that 130

the gas envelop or balloonnet chambers outside the envelops and balloonnets can be ventilated and kept cool, and any escaping gases discharged.

5 In some cases, as shown in the drawings, air ventilating ducts or shafts 35 may be provided on each side of the air passage 10, extending from the intermediate deck 2 to the shaft 23, for the purpose of extracting 10 air gases that may find their way upward around the gas envelops under the deck 2— see Figs. 5, 7, and 8.

Between the successive chambers 4, and also between the chambers 3, the lattice 15 struts or columns 37 are provided, between the bottom of the ship and the deck 2, and the deck 2 and the roof of the casing 1; and the passages 10 and 11 pass between the side members of these struts at their lower 20 portion; while through the upper struts the main air shaft 23 passes, and is supported by them as seen in Fig. 14. These struts not only serve the purpose of supporting the passages and air shaft, but also give vertical 25 and general rigidity to the structure.

Propellers 40 are provided into the lower intersection chambers 3, and they are adapted to be run out of carrier frames 41, through suitable apertures in the sides of 30 the ship, and are revolved when outboard; and when not required, can be housed inside the chambers 3 as shown in Fig. 4.

At the stern of the ship, another propeller 42 is provided; and it is operated from a 35 motor in the stern chamber or space 43, which will be suitably divided into several stories by decks, some of which will serve as gun decks; others for engine decks; or for any other purpose as may be desired. 40 The lower and upper chambers 3 and 4 also will be provided with decks, 45 and 46, which may serve as gun decks, or living decks, and engine room decks, as may be desired; and communication will be had, one 45 with the other by means of ladders. Bomb wells may be provided in the lower deck of the chamber 3 and fore and stern chambers and also in the floor of the passage 11.

The water ballast tanks 6 and oil tanks 7 50 as shown in Fig. 4, are disposed below the lower deck 46 of these chambers 3.

In the space between the intermediate horizontal deck 2, and the upper part of the framing 1, and extending between two of 55 the chambers 4, there will be four gas envelops, two on each side. And, similarly, in the lower half of the ship, there will be four gas envelops two on each side between the chambers 3, and at the center point between 60 each pair of chambers where the gas envelops end there is a bellows form of bag or balloonnet adapted to contain gas or air, and which serves the purpose of allowing for the expansion of the gas in the gas 65 envelops; and also gas or air, as the case may

be, contained in these bellows vessels, may be forced into it, or let out, as occasion may require.

The gas envelops may thus always be kept at a proper tension, neither too great a pressure, or too small a pressure. 70

The general framing of the machine may consist of longitudinal members 47 of wood, provided with notches which pass through and engage in notches in the vertical or circumferential members 48, so that the surface of these longitudinal and transverse frame members are flush; and the upper part of the ship, inside may be suitably boarded at 50; and otherwise the interior of the frame work 80 may be covered with perforated metal, metal meshwork or netting, against which the surface of the gas envelops rests.

Beneath the deck 2, there may be light timbering or wire or other covering 51 which 85 take up the strain of and prevent the envelops from bulging into the frame spaces and stopping ventilation.

Through the frame joints and metal angle cleats 53 of the frames 47, 48, diagonal bracing wires 54 pass, and they are gripped in these holes by set screws 55, screwing into holes in them, and so they are firmly clamped and bound; and this diagonal bracing strengthens the whole framing; and at the 95 same time is very light. Furthermore, these braces 54 are bound together where they cross within the frame spaces, by clamps, as seen in Figs. 10, 11 and 12, consisting of a lower plate 57, having a shank 58 upon it 100 with cross cuts through it, down which the wires may pass, so as to lie in grooves on the plate 57; and the wires are clamped in this position by a washer or plate 59 fitting over the shanks 58, and held in position and 105 clamped therein by a nut 60 screwing over the shank.

A cruciform key 61 (shown in Fig. 12) is let down into the slots in the shank 58; and one member, longer than the others, passes 110 down through a gap on the inside of the nut 60, so that when the key is inserted the nut cannot slack back.

A detail of the frame members 47 and 48 is shown in Fig. 18, and the outer cover 68 115 is secured to these; and where the edges of the outer cover or sheathing of textile or like material comes, a strip of rubber is inserted between them, and their edges are clamped down by nuts 69 screwing over screws 70, 120 screwed into the member; and a washer plate 71 is provided between the nut 69 and the outer cover 68.

The fore chamber 62 of the ship, similarly to the stern chamber 43, may be divided into 125 suitable rooms by horizontal decks or platforms, and used for gun decks or living decks or cabins, and any other purpose that may be desired.

On both sides of the ship planes 65 may 130

be employed projecting out from same, with their forward ends lifted and their after ends depressed, as indicated in Fig. 1, and serve the purpose as side keels and give 5 general stability of movement; and also on the outside of the ship (see Fig. 19) movable vertical wings 66 may be provided and mounted on vertical hinges at their inner edges, which serve as a means for assisting 10 steering as one or the other set of wings on the opposite side of the ship are moved out and in.

Windows or ports will be provided in the 15 sides of the chambers 3 and 4, for observation and light, and training guns through, or other purposes, as may be desired.

Both frames 47 and 48 are provided with a multiplicity of holes 72 through them, for the purpose of providing free access to the 20 spaces inclosed by these frames, and so that ventilation all round the envelops and ship throughout can take place, and a free movement of air be provided for.

The outer skin or covering is air and water- 25 proof, along the bottom; and for some distance up each side, say about six feet, where it is exposed to water pressure, a special protection is employed, comprising a double material with a light steel ring netting 30 pressed between the double material, and held together by a suitable adhesive.

By the forms and sections of parts referred to, the ship is better enabled to resist pressure, and affords generally, a strong section, both as regards external forces, and 35 internal forces.

By means of the various spaces and chambers, and the use of sliding or the like doors, as referred to, on each side of the chambers, 40 and in the passages, air can be forced through into one or more of the sections, the sliding parts being adapted to close or open a passage as the case may be, when it is required to deliver air to any special chamber; 45 so that by this means, any of the upper or lower gas envelops may be supplied with a cool current of air. Furthermore, these vertical tubes connected with the lifting propellers, carry off the air moved by them, 50 rapidly, and so increase the efficiency of the lifting propellers as such.

Abaft each junction of a lifting propeller tube 24, and the fore and aft tubes 23 a high speed fan 27 may be provided, for assisting 55 in forcing the air along the fore and aft tube. By this air tube system, the propelling of the ship, and its steering may be very much assisted and promoted.

With regard to the compensating ballonnets, these may consist of bags or envelops; and instead of being inflated with air, they are inflated with the same gas as is contained in the envelops; and should the pressure in these main envelops increase, the 60 ballonnets would be compressed and closed

in like an accordion, and some of this gas would be adapted to be discharged through a relief valve, if the pressure becomes high; while, at the same time, the gas or lifting capacity would not be reduced. Further, 70 with the continuous current of air throughout the ship, in the manner described, no great or sudden change in temperature of the gas and its expansion could take place easily. And in connection with the ballonnets, hot and cold injectors may be carried, so that the gas in these could be kept to the standard required; and they being comparatively narrow envelops, having a large area over which hot or cold gases 80 could pass, they would allow considerable expansion in the gas envelops.

What is claimed is:—

1. In a ship capable of being supported by air (and water) comprising a plurality 85 of sections containing gas holders, the combination of sectional division chambers, a horizontal deck extending through the ship, and columns, as 37, extending vertically through the ship, and disposed at a point or 90 points intermediate the sectional division chambers 3 and 4; substantially as described.

2. In a ship capable of being supported by air (and water) comprising a plurality 95 of sections containing gas holders, the combination of sectional division chambers, and a horizontal deck extending through the ship and wherein the gas holders in each section have between them, a bellows gas holder; substantially as and for the purposes set forth. 100

3. A ship capable of being supported by air (and water) comprising a plurality of sections containing gas holders, separated by relatively narrow sectional division chambers, and of the form substantially of a horseshoe in cross section, with the "heels" 105 at the lower part; substantially as described.

4. A ship capable of being supported by air or water comprising a plurality of sections containing gas holders, a horizontal deck extending through the ship, a plurality of upper and lower chambers formed by said deck, an air duct extending longitudinally through the length of the ship situated in 110 the upper part of the ship, and columns extending vertically through the ship disposed at points intermediate the upper chambers and intermediate the lower chambers. 115

5. A ship capable of being supported by 120 air or water comprising a plurality of sections containing gas holders, separated by relatively narrow sectional division chambers and of the form substantially of a horseshoe in cross section with "heels" at the 125 lower part and an air duct extending longitudinally throughout the length of the ship having means at its stern end whereby said ship may be steered.

6. A ship capable of being supported by 130

air or water comprising a plurality of sections containing gas holders, the combination of sectional division chambers and a horizontal deck extending through the ship, a tunnel directly above the deck, and an air shaft extending longitudinally through the ship from bow to stern with air inlet branches in it, an expanded and downwardly directed "nose" at the bow end of said shaft, and means whereby the entrance of air therein may be regulated.

7. A ship adapted to be supported by air or water comprising a framework substantially of the form of a horseshoe in cross section, waterproof covering for said framework, a plurality of sections containing gas holders within said framework and covering, and "heels" formed by the lower ends of said frame forming longitudinally extending keels for said ship.

8. A ship capable of being supported by air or water comprising a framework substantially of horseshoe form in cross section, a covering for said framework, a horizontally disposed slightly concave deck extending throughout the length of the framework, a plurality of sections containing gas holders within said framework, and columns extending vertically through the ship and disposed at points within and along the longitudinal center line of said sections.

9. A ship capable of being supported by air or water comprising a plurality of sectional division chambers, intermediate gas holder sections, vertical columns intermediate said sectional division chambers, said vertical columns supporting an air shaft passing from the bow to the stern of said ship, said columns open centrally and form-

ing passages through said sections, and a 40 horizontal deck approximately at the center of said ship.

10. A ship capable of being supported by air or water comprising a plurality of sectional division chambers, intermediate gas holder sections, a horizontal deck intermediate the top and bottom of said ship, passages extending through the center of the ship on said horizontal deck, and passages extending through the center of the ship on 50 the bottom of said ship, vertical columns in the center of said ship intermediate said sectional division chambers, an air shaft passing through the upper half of the ship from bow to stern having vertical air passages extending upward through the top of said ship, and means whereby air may be forced through said main shaft and auxiliary shafts.

11. A ship capable of being supported by 60 air or water comprising a plurality of sectional division chambers, intermediate gas holder sections, bellows gas holders between said sections, a horizontal deck passing through said ship, vertical columns at the 65 center of said ship intermediate said sectional division chambers, an air duct supported by said columns passing through said ship from bow to stern and containing means at its after end whereby said ship might be 70 steered horizontally.

In testimony whereof I have signed my name to this specification in the presence of two subscribing witnesses.

GEORGE SUTHERLAND DODMAN.
